(57) **CLAIM**

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is a front view of a display screen or portion thereof with graphical user interface showing the claimed design. The dot-dash broken lines in the figures show boundaries or portions of the graphical user interface that form no part of the claimed design.

The bold dashed broken lines in the figures connecting solid line portions of the design form part of the claim.

1 Claim, 1 Drawing Sheet

FIG. 2

UNITED STATES PATENT AND TRADEMARK OFFICE
CERTIFICATE OF CORRECTION

PATENT NO. : D913,319 S
APPLICATION NO. : 29/678932
DATED : March 16, 2021
INVENTOR(S) : Day et al.

Page 1 of 1

It is certified that error appears in the above-identified patent and that said Letters Patent is hereby corrected as shown below:

On the Title Page

In the description item (57), please add the following paragraph to the end of the description:
“The outermost broken lines in the figures show a display screen or portion thereof, and form no part of the claimed design.”

Signed and Sealed this
Twenty-seventh Day of July, 2021

Drew Hirshfeld
